UNITED STATES PATENT OFFICE.

JAMES F. McCLOSKEY, OF WILMINGTON, DELAWARE, ASSIGNOR, BY MESNE ASSIGNMENTS, TO FORD & MANION, OF WILMINGTON, DELAWARE, A CORPORATION OF DELAWARE.

DESIGN FOR AN ELECTRIC IMMERSION HEATER.

60,496.

Specification for Design.

Patented Feb. 28, 1922.

Application filed August 11, 1921. Serial No. 491,584. Term of patent 14 years.

To all whom it may concern:

Be it known that I, JAMES F. McCLOSKEY, a citizen of the United States of America, residing at Wilmington, in the county of New Castle and State of Delaware, have invented a new, original, and ornamental Design for Electric Immersion Heaters, of which the following is a specification, reference being had to the accompanying drawings, forming a part thereof.

Fig. 1 is an elevation of the electrical immersion heater of my new design,

Fig. 2 is a top plan view, and

Fig. 3 is an under or bottom view of the same.

What is claimed is:

The ornamental design for an electric immersion heater, as shown.

JAMES F. McCLOSKEY.
